UNITED STATES PATENT OFFICE

2,646,840

UPHOLSTERED SEAT STRUCTURE

Wayne W. Good, Sturgis, Mich., assignor to
Harter Corporation, Sturgis, Mich.

Application March 15, 1951, Serial No. 215,673

9 Claims. (Cl. 155—180)

1

This invention relates to improvements in upholstered seat structure.

The main objects of this invention are:

First, to provide an upholstered seat structure which is well adapted for office and store chairs, stools and the like, which is simple and economical in its parts, has a finished attractive appearance and permits a wide selection of covering, both in the original upholstery and for recovering as occasion may require or render desirable.

Second, to provide an upholstered seat structure in which the upholstery may be applied by unskilled workmen and with the aid of simple tools or appliances.

Third, to provide a structure having these advantages which may be very economically produced and at the same time is very durable.

Objects relating to details and economies of the invention will appear from the description to follow. The invention is defined and pointed out in the claims.

A preferred embodiment of the invention is illustrated in the accompanying drawing, in which:

Fig. 1 is a fragmentary elevational view partially in section on a line corresponding to the broken line 1—1 in Fig. 2.

Fig. 2 is a fragmentary inverted view of the seat removed from the pedestal.

Fig. 3 is an enlarged fragmentary perspective view partially in section.

Fig. 4 is an enlarged fragmentary view mainly in section on a line corresponding to line 4—4 in Fig. 2.

Fig. 5 is a perspective view of the upholstery clamping members disassembled.

In the accompanying drawing, 1 represents the post or pedestal and 2 represents a spider-like bracket on the upper end of the post for supporting the seat structure. The seat structure comprises a base plate 3 formed as a sheet metal stamping and having a downturned rim 4 terminating in an inturned curved flange 5. The base plate 3 is provided with a pair of spaced parallel ribs 6—6 to which the upwardly facing U-shaped bars 7 are fixedly secured as by spot welding at 8. Attaching bolts 9 are secured to these reinforced ribs 6, these being adapted to receive the arms of the supporting bracket 2 which are secured on bolts by means of the nuts 10. The base plate 3 has parallel reinforcing ribs 11 disposed transversely of the ribs 6. It is also provided with radial ribs 12 radiating from the outward annular rib 13. This

2

permits the base plate being formed of relatively light sheet metal stock but is rigid in all directions and capable of carrying heavy loads. Air vent holes 14 are provided. The upholstery

5 in the embodiment illustrated comprises a rubber cushion 15 disposed on the base plate, an adhesive 16 being preferably applied over the base and around the flanges thereof. The upholstery cover 17 is provided with a skirt portion 18 surrounding the edge of the cushion and folded inwardly around the lower edge of the rim against the inner side thereof and lapped upon the underside of the base. The upholstery is clamped in position by means of the U-shaped 10 clamping members 19 and 20. The clamping member 19 is of U shape, the arms 21 thereof being springable and provided with inwardly offset end portions 22 terminating in lugs 23 engaged with holes 24 in the clamping strip 20.

15 With the upholstery draped or folded around the rim, the clamping members are inserted into clamping engagement with the inturned part of the upholstery as is illustrated in the drawings, and the arms of the U-shaped member 20. Desirably the clamping members are of such 20 width that they lie above the inturned flange 5 and snubbingly engage the upholstery covering between the lower edges of the clamping member and the flange and between the upper edges

25 of the clamping member and the base plate. To further secure the clamping members, the base plate is provided with bendable tongues 25 which are folded downwardly into retaining engagement with the clamping members. This provides 30 means for very securely retaining the upholstery while enabling the assembly thereof by relatively inexperienced workmen and permitting the assembly of the upholstery by a dealer to meet the requirements of a particular customer, or to permit reupholstery and recovering as occasion may 35 require.

I have illustrated and described a highly practical embodiment of my invention. I have not attempted to illustrate or describe other embodiments or adaptations as it is believed that this disclosure will enable those skilled in the art to embody or adapt my invention as may be desired.

40 Having thus described my invention, what I claim as new and desire to secure by Letters Patent is:

45 1. In an upholstered seat structure, the combination of a metal base plate having a downturned rim terminating at its lower edge in an

50 55

inwardly directed flange, an upholstery covering embracing said rim and folded upwardly around the said rim flange and against the inner side thereof and lapping upon the underside of the base plate, a U-shaped upholstery clamping member disposed within said rim upon the upturned upholstery covering and having springable arms, said arms being offset inwardly at their ends and terminating in lugs, and a second upholstery clamping member disposed within said rim in opposed relation to said U-shaped clamping member and having holes therein with which the lugs of said springable arms are retainingly engaged, said clamping members being of such width as to snubbingly engage the upholstery covering between the inner side of the rim flange and the base plate, said base plate having bendable tongues engaging the inner sides of said clamping members.

2. In an upholstered seat structure, the combination of a metal base plate having a downturned rim, an upholstery covering embracing said rim and folded upwardly around and against the inner side thereof, a U-shaped upholstery clamping member disposed within said rim upon the upturned upholstery covering and having springable arms, said arms being offset inwardly at their ends and terminating in lugs, and a second upholstery clamping member disposed within said rim in opposed relation to said U-shaped clamping member and having holes therein with which the lugs of said springable arms are retainingly engaged, said base plate having bendable tongues engaging the inner sides of said clamping members.

3. In an upholstered seat structure, the combination of a metal base plate having a downturned rim terminating at its lower edge in an inwardly directed flange, an upholstery covering embracing said rim and folded upwardly around the said rim flange and against the inner side thereof and lapping upon the underside of the base plate, a U-shaped upholstery clamping member disposed within said rim upon the upturned upholstery covering and having springable arms, said arms being offset inwardly at their ends and terminating in lugs, and a second upholstery clamping member disposed within said rim in opposed relation to said U-shaped clamping member and having holes therein with which the lugs of said springable arms are retainingly engaged, said clamping members being of such width as to snubbingly engage the upholstery covering between the inner side of the rim flange and the base plate.

4. In an upholstered seat structure, the combination of a metal base plate having a downturned rim, an upholstery covering embracing said rim and folded upwardly around and against the inner side thereof, a U-shaped upholstery clamping member disposed within said rim upon the upturned upholstery covering and having springable arms, said arms being offset inwardly at their ends and terminating in lugs, and a second upholstery clamping member disposed with-

in said rim in opposed relation to said U-shaped clamping member and having holes therein with which the lugs of said springable arms are retainingly engaged.

5. In a seat structure, the combination of a base plate having a downturned rim terminating at its lower edge in an inwardly directed flange, a U-shaped upholstery clamping member disposed within said rim and having springable arms, said arms being offset inwardly at their ends and terminating in lugs, and a second upholstery clamping member disposed within said rim in opposed relation to said U-shaped clamping member and having holes therein with which the lugs of said springable arms are retainingly engaged, said base plate having bendable tongues engaging the inner sides of said clamping members.

6. In a seat structure, the combination of a base plate having a downturned rim, a U-shaped upholstery clamping member disposed within said rim and having arms terminating in lugs, and a second upholstery clamping member disposed within said rim in opposed relation to said U-shaped clamping member and having holes therein with which the lugs of said springable arms are retainingly engaged.

7. In a seat structure, the combination of a metal base plate having a downturned rim terminating at its lower edge in an inwardly directed flange, a U-shaped upholstery clamping member disposed within said rim, and a second upholstery clamping member disposed within said rim in opposed relation to said U-shaped clamping member and engaged with the arms thereof, said base plate having bendable tongues engaging the inner sides of said clamping members.

8. In a seat structure, the combination of a metal base plate having a downturned rim, a U-shaped upholstery clamping member disposed within said rim, and a second upholstery clamping member disposed within said rim in opposed relation to said U-shaped clamping member and engaged with the arms thereof.

9. In a seat structure, the combination of a metal base plate having a downturned rim, a U-shaped upholstery clamping member disposed within said rim and having springable arms, and a second upholstery clamping member disposed within said rim in opposed relation to said U-shaped clamping member and supportingly engaged with the arms thereof, said base plate having tongues engaging the inner sides of said clamping members.
